W. JAY,
VACUUM FUEL FEED TANK CONSTRUCTION,
APPLICATION FILED OCT. 16, 1919.

1,370,450.

Patented Mar. 1, 1921.

UNITED STATES PATENT OFFICE.

WEBB JAY, OF CHICAGO, ILLINOIS.

VACUUM FUEL-FEED TANK CONSTRUCTION.

1,370,450.

Specification of Letters Patent.

Patented Mar. 1, 1921.

Application filed October 16, 1919. Serial No. 331,107.

To all whom it may concern:
Be it known that I, WEBB JAY, a citizen
of the United States, residing at Chicago, in
the county of Cook and State of Illinois,
5 have invented certain new and useful Im-
provements in Vacuum Fuel-Feed Tank
Construction, of which the following is a
specification, reference being had to the ac-
companying drawings, forming a part
10 thereof.

The purpose of this invention is to pro-
vide an improved construction for the tanks
of vacuum fuel feed devices. It consists in
the elements and features of construction
15 shown and described, as indicated in the
claims.

In the drawings:

The figure is a vertical axial section of
vacuum fuel feed tanks embodying this in-
20 vention.

The specific purpose of the present inven-
tion is to simplify and cheapen the cost of
manufacture of the tanks of vacuum fuel
feed devices of a well known type which
25 comprise a vacuum chamber A, and a re-
serve chamber B, with vacuum, air inlet and
liquid inlet connections to the vacuum cham-
ber, an outlet valve from the vacuum cham-
ber to the reserve chamber, and supply con-
30 nections from the reserve chamber to the
carbureter, and a drainage connection, and
which comprise an annular chamber or ex-
tension of the reserve chamber encompassing
the vacuum chamber for the purpose of pro-
35 viding for expansion of the contents of said
reserve chamber under heat to which the
device is frequently exposed. For the pur-
pose of economy and simplicity of construc-
tion in embodying these necessary elements,
40 the tank shown comprises a main body mem-
ber, 1, which is cylindrical in form and is
preferably formed cup-shaped,—that is to
say, spun or pressed or formed otherwise
from a single sheet of metal so as to have a
45 closed bottom and an open top, said one-
piece member comprising both the vacuum
chamber and the reserve chamber which are
partitioned from each other by a transaxial
partition, 2, most conveniently formed also
50 in cup form, adapted to fit within the cylin-
drical body member and be permanently se-
cured thereto by well known methods, as by
sweating, so as to make a liquid-tight and
air-tight junction. Immediately below the
55 plane of the transaxial partition, 2, the
member, 1, has a series of apertures, 3, open-

ing into the lower chamber B,—the reserve
chamber;—and outside said body member, 1,
there is fitted upon it a sleeve, 4, whose
diameter throughout its length in general 60
is enough greater than the outside diameter
of the body member, 1, to constitute an an-
nular chamber, 4^a, between said body mem-
ber and said sleeve; the lower end of said
sleeve being contracted as shown at 4^b, to fit 65
snugly on the outer surface of the cylin-
drical body member, 1, and to be united per-
manently thereto as by sweating, forming an
air-tight and liquid-tight junction. At the
upper end of the body member, 1, there is 70
provided a terminal fitting, 5, angular in
cross-section so as to form a cylindrical sleeve
flange, 5^a, whose thickness is substantially
the width of the annular interspace between
the sleeve, 4, and the said body member, 1, 75
so that it fits therein and may be perma-
nently joined to both said parts to close at
the upper end the annular chamber, 4^a. The
horizontal flange of said fitting serves for
securing the cap member, 6, which carries as 80
usual, suction, air and liquid fuel inlet con-
nections, 8, 9 and 10, respectively. 11 is the
usual outlet valve from the upper chamber,
A, to the lower chamber, B. An atmos-
phere connection with the annular chamber, 85
4^a, is conveniently made through the spac-
ing flange, 5^a, as seen at 5^b, registering with
an aperture, 6^a, in the cap member, 6, with
which connection will be made for vapor
discharge at any desired distance from and 90
away from the device as indicated by the
pipe, 9^a. 12 and 13 are respectively the car-
bureter connection and the drainage con-
nection from the chamber, B.

I claim:—

1. In a device for the purpose indicated, a
receptacle having a transaxial partition in-
termediate its upper and lower ends, defin-
ing an upper chamber having an atmos-
pheric, a suction and a liquid supply con-
nection, and a lower chamber having a liquid
outlet; said partition having an outlet valve
from the upper to the lower chamber; a
sleeve adapted at its lower end to fit outside
the receptacle and having its upper portion 105
of greater diameter than the outer diameter
of the receptacle for forming an annular
chamber around said receptacle, and a ter-
minal fitting for the upper end of the re-
ceptacle having a flange embracing said 110
upper end and serving to space the upper
end of the sleeve from the outer surface

of the receptacle and occupy the space, the receptacle having apertures at a transaxial plane below the plane of the transaxial partition and above the plane of the junction of the lower contracted end of the sleeve with the outer wall of the receptacle.

2. In a device for the purpose indicated, a receptacle comprising a one-piece body member of substantially cylindrical form with an integral bottom and open top; a sleeve adapted to be passed outside of said cylindrical member, having its lower end contracted to fit the outer surface of the latter and spaced away from the said outer surface from said contracted lower end; a fitting for the upper end of the body member adapted to close the upper end of the an-

nular cavity formed between said sleeve and said body member, said body member having apertures at a transaxial plane above the zone of junction of said sleeve at its lower end with the said body member, and a transaxial partition in said member above the plane of said aperture; a cap for said receptacle having suction, atmosphere inlet and liquid inlet connections, and a valve controlling flow from the chamber above said partition to the chamber formed below the same.

In testimony whereof, I have hereunto set my hand at Chicago, Illinois, this 13 day of October, 1919.

WEBB JAY.
